UNITED STATES PATENT OFFICE.

STANLEY G. JOHNSON, OF DETROIT, MICHIGAN, ASSIGNOR TO THE BURKHARDT COMPANY, OF DETROIT, MICHIGAN, A CORPORATION OF MICHIGAN.

DISPLAY BOOK.

Application filed December 18, 1926. Serial No. 154,602.

This invention relates to display books and devices, more especially of the loose leaf type, wherein it is often desirable to provide for the support of the leaves at a suitable angle so that any of them may be exposed to view and held in such exposed position indefinitely, and the object of the invention is to provide a simple arrangement of cover and fly-leaf or member which will cooperate in the support of any of the leaves of the device as required and which are adapted to cooperate in the maintaining of the devices as a whole in an adjusted display condition.

The invention further contemplates the utilizing of certain portions of the cover of the device as a means for directly supporting the fly-leaf in a raised display position and the utilizing of the fly-leaf through the medium of a brace for the maintaining of the front and back of the cover in angular easel formation and against diverging from one another to an extent which would result in the collapse of the cover as a supporting structure for the leaves of the device.

Further objects subsidiary to or resulting from the aforesaid objects or from the construction or operation of the invention as it may be carried into effect will appear as the said invention is hereinafter further disclosed.

In carrying the said invention into effect I may utilize a binder cover having front and back boards hingedly connected to an intermediate member, and a loose leaf binder mechanism such as a ring binder, mounted on one of said boards proximate to said intermediate member and carrying loose leaves as well as a fly-leaf of relatively stiff material. The cover is adapted to be reversed from its normal closed position to provide an inverted V-shaped easel composed of the back and front boards thereof, with the intermediate portion maintained in alinement with the back portion of the cover which then becomes the front portion of the easel due to the reversal of the cover. The maintenance of this alinement of the back and intermediate portions of the cover is effected by the fly-leaf which is provided with fastening means for its attachment to the said intermediate portion whereby the said fly-leaf forms a connection between the intermediate portion and the ring binder by which the fly-leaf is carried. A flexible brace is mounted on the upper side of the fly-leaf

which becomes the back thereof and in its raised display position, and this flexible member is adapted to be extended over and secured to the front cover which is then the back of the easel to prevent its slipping on the surface on which the device may be supported.

All of which is more particularly described and ascertained hereinafter, by way of example, having reference to the accompanying drawing, wherein—

Figure 1 is a perspective view of a device embodying the said invention illustrating the same in its display condition;

Figure 2 is a perspective view indicating the back of the same;

Figure 3 is a fragmentary detail side elevation partly in section of the device;

Figure 4 is a plan view of the device closed, with the exception of the cover, which is shown open; and

Figure 5 is a side elevation of the device in its fully closed position.

Similar characters of reference indicate similar parts in the several figures of the drawing.

1 and 2 are the front and back members of a stiff board covering, the said members being hingedly attached at 3 and 4 to an intermediate member 5 of a more or less rigid nature, and 6 is a book of leaves carried by the rings 7 of a binder mechanism 8.

In ordinary loose leaf binder practice, it is usual to attach the binder mechanism to the intermediate member 5 of the cover, but in the present case I mount it on one or other of the members 1 and 2, in the example, the member 2, proximate to the intermediate member 5, so that the rings 7 occupy practically the same position within the cover as they would if the mechanism were actually attached to the said intermediate member 5, and thus do not materially effect the position of the loose leaf 6 within the cover. Also carried by the binder mechanism through the medium of the rings 7 is a fly-leaf 9 of relatively stiff material.

The cover of the device is adapted to be set up in the form of an easel as shown in Figures 1, 2 and 3, by reversing the member 1 on its hinge 3 so that it may form the rear support of the easel, and the members 2 and 5 the front of the easel carrying the binder mechanism and parts mounted there-

on, including the leaves 6 and fly-leaf 9, and it will be noted that the intermediate member 5 is provided with studs 10 and the fly-leaf with snap fasteners 11 adapted to engage the said studs 10 when the fly-leaf is raised to the position indicated in Figures 1, 2 and 3, so that the said fly-leaf when so raised and engaged with the studs 10 braces the intermediate portion 5 of the cover from the rings 7 of the binder and maintains the said intermediate member 5 extended practically in the same plane as the member 2 of the cover as very clearly illustrated in Figure 3, and in turn the said fly-leaf is secured in an upwardly extending position from the binder mechanism and from the intermediate member 5 of the cover forming a support for such of the leaves 6 as may be also moved to such upwardly extended position for display purposes as shown in dotted lines in Figure 3. The fly-leaf 5 is therefore in its display position supported by virtue of its two point connection to the front of the easel at the studs 10 and the rings 7.

Ordinarily the members 1 and 2 when operating as an easel may if resting upon a smooth surface tend to spread apart and result in the collapsing of the device when in use, and to prevent this I provide the fly-leaf with a flexible brace 12 pivotally mounted at 13 on the said fly-leaf, so that it may be turned to operative position as shown in Figures 1 to 3 or out of operative position as shown in Figures 4 and 5, when the cover is closed, this brace being provided with an orifice 14 at the end of its longer arm to receive a stud 15 on the member 1 of the cover when used as an easel, so that the said brace may be connected to the said member 1 as clearly indicated in Figure 3 to form a resistance to the undue spreading of the members 1 and 2 of the easel when in use. Incidentally, although this is not its principal object, due to the support already indicated for the fly-leaf, this brace may also form a secondary support for the fly-leaf when in display position where the leaves resting against the fly-leaf are of such weight that the said brace is required to function as such secondary support.

It will be observed that the construction described is very simple, varying very little from the ordinary binder so far as general appearance is concerned when it is closed, and being no more bulky, so that when not used actually as a display stand it may be used much in the same manner as an ordinary loose leaf binder for inspection of material bound therein, there being beyond the fly-leaf 9 and the parts carried thereby and the studs on the cover of the binder, no additional extension or attachments to interfere with such use in the ordinary manner. Thus

it may be readily used as a stenographer's note book, a salesman's catalogue, a show-card display device, and for innumerable other purposes which may suggest themselves.

This invention may be developed within the scope of the following claims without departing from the essential features of the said invention, and it is desired that the specification and drawing be read as merely illustrative and not in a limiting sense, except as necessitated by the prior art.

What I claim is:—

1. In a binder, a cover adapted to be reversed from a normal closed position to provide an inverted V-shaped easel, said cover comprising front and back boards hingedly connected to the edges of an intermediate member, a loose-leaf binder mechanism mounted on one of said boards proximate to said intermediate member, a fly-leaf of stiff material carried by said binder mechanism, and means for securing said fly-leaf in a raised position to the intermediate member of said cover whereby said fly-leaf is supported in a raised position and maintains said intermediate portion in practical alignment with the cover board forming the front of the easel.

2. In a binder, a cover adapted to be reversed from a normal closed position to provide an inverted V-shaped easel, said cover comprising front and back boards hingedly connected to the edges of an intermediate member, a loose-leaf binder mechanism mounted on one of said boards proximate to said intermediate member, a fly-leaf of stiff material carried by said binder mechanism, and means for fastening said fly-leaf in a raised position to the front of said easel whereby said fly-leaf is maintained in such raised position by a part of the front of said easel extending above said binder mechanism.

3. In a binder, a cover structure flexible across a transverse line whereby it may be reversed from a normally closed position to provide an inverted V-shaped easel, a binder mechanism and a fastening element carried by said structure at the same side of said transverse line, a fly-leaf hingedly attached to said binder mechanism, and a fastening element carried by said leaf and adapted to cooperate with the first named element.

4. In a binder, a cover structure flexible across a transverse line whereby it may be reversed from a normally closed position to provide an inverted V-shaped easel, a binder mechanism and a fastening element carried by said structure at the same side of said transverse line, a fly-leaf hingedly attached to said binder mechanism, a fastening element carried by said leaf and adapted to cooperate with the first named element, and a brace adapted to connect said fly-leaf with

the portion of the structure at the other side of said transverse line.

5. In a binder, a cover structure flexible across a transverse line whereby it may be reversed from a normally closed position to provide an inverted V-shaped easel, a binder mechanism and a fastening element carried by said structure at the same side of said transverse line, a fly-leaf hingedly attached

to said binder mechanism, a fastening element carried by said leaf and adapted to cooperate with the first named element, and a slightly flexible brace adapted to connect said fly-leaf with the portion of the structure at the other side of said transverse line. ¹⁰ ¹⁵

In testimony whereof I affix my signature.

STANLEY G. JOHNSON.
